(57) **CLAIM**

The ornamental design for a packaging box, as shown and described.

DESCRIPTION

FIG. 1 is an exploded front perspective view of a packaging box showing our new design with a tray that forms no part of the claimed design to show environment; FIG. 2 is an exploded front elevation view thereof; FIG. 3 is an exploded rear elevation view thereof; FIG. 4 is an exploded right side elevation view thereof; FIG. 5 is an exploded left side elevation view thereof; FIG. 6 is an exploded top plan view thereof; FIG. 7 is an exploded bottom plan view thereof; and, FIG. 8 is a front perspective view thereof, in which the packaging box is shown separately for ease of illustration. The tray shown in evenly dash-dot line illustrates environmental structure and forms no part of the claimed design. The remaining evenly dash-dot line depict portions of the packaging box that form no part of the claimed design. The long-short dash line in FIG. 3 illustrates a boundary line that forms no part of the claimed design.
